US0D1073451S

(12) **United States Design Patent** (10) **Patent No.:** **US D1,073,451 S**
(45) **Date of Patent:** **** May 6, 2025**

(54) **ROLLER SHADE BRACKET**

(71) Applicant: **Crestron Electronics, Inc.**, Rockleigh, NJ (US)
(72) Inventors: **Fang Lin**, Staten Island, NY (US); **Hanna Bondarik Mosolygo**, West Milford, NJ (US)

(73) Assignee: **Crestron Electronics, Inc.**, Rockleigh, NJ (US)

(**) Term: **15 Years**

(21) Appl. No.: **29/895,783**

(22) Filed: **Jun. 26, 2023**

(51) **LOC (15) Cl.** **08-05**

(52) **U.S. Cl.**

USPC **D8/363; D6/580**

(74) *Attorney, Agent, or Firm* — Crestron Electronics, Inc.

(57) **CLAIM**

The ornamental design for a roller shade bracket, as shown and described.

DESCRIPTION

FIG. 1 shows a front inner perspective view of a roller shade bracket.

FIG. 2 shows a front outer perspective view thereof.

FIG. 3 shows a rear inner perspective view thereof.

FIG. 4 shows an outer side view thereof.

FIG. 5 shows an inner side view thereof.

FIG. 6 shows a top view thereof.

FIG. 7 shows a bottom view thereof.

FIG. 8 shows a front view thereof.

FIG. 9 shows a rear view thereof; and,

FIG. 10 shows a perspective disassembled view thereof. The broken lines in the figures depict portions of the roller shade bracket that form no part of the claimed design.

1 Claim, 8 Drawing Sheets
